US00D961567S

(12) **United States Design Patent** (10) Patent No.: **US D961,567 S**
(45) Date of Patent: **** Aug. 23, 2022**

(54) **ELECTRONIC DEVICE**

(71) Applicant: **Samsung Electronics Co., Ltd.**, Suwon-si (KR)

(72) Inventors: **Junyong Song**, Suwon-si (KR); **Byoungjin Kim**, Suwon-si (KR); **Woohyeok Jeong**, Suwon-si (KR); **Eunsoo Kim**, Suwon-si (KR); **Junghyun Choi**, Suwon-si (KR)

(73) Assignee: **SAMSUNG ELECTRONICS CO., LTD.**, Suwon-si (KR)

(**) Term: **15 Years**

(21) Appl. No.: **29/748,582**

(22) Filed: **Aug. 31, 2020**

(30) **Foreign Application Priority Data**

Apr. 27, 2020 (KR) 30-2020-0018524

(51) LOC (13) Cl. **14-03**

(52) U.S. Cl.

USPC **D14/248**

(58) **Field of Classification Search**

USPC .... D14/348, 426, 439, 496, 138 R, 138 AA, D14/138 AB, 138 AC, 138 AD, 138 C, D14/138 G, 203.1, 203.3, 203.4, 203.7, D14/299; D10/50

(57) **CLAIM**

The ornamental design for an electronic device, as shown and described.

DESCRIPTION

FIG. 1 is a front perspective view of an electronic device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear perspective view thereof.

The broken lines in the figures illustrate portions of the electronic device that form no part of the claimed design.

1 Claim, 8 Drawing Sheets
